UNITED STATES PATENT OFFICE.

WILLIAM DAN DALGLEISH, OF STAMFORD, CONNECTICUT.

DESIGN FOR A MUSTACHE-GUARD CLIP.

SPECIFICATION forming part of Design No. 26,508, dated January 12, 1897.

Application filed November 17, 1896. Serial No. 612,508. Term of patent 7 years.

To all whom it may concern:

Be it known that I, WILLIAM DAN DALGLEISH, of Stamford, in the county of Fairfield and State of Connecticut, have invented 5 and produced a new and original Design for a Mustache-Guard Clip, of which the following is a full, clear, and exact description.

Reference is to be had to the accompanying drawing, forming a part of this specification, 10 in which the figure represents a perspective view of a mustache-guard clip embodying my new design.

The design consists of a clip approximately of U shape, the inner member being thickened at the edge and tapering toward the 15 bend of the clip.

The leading feature of the design consists of the mustache-guard clip, approximately of U shape and having one member thickened at the free edge and tapering toward the bend 20 of the clip.

I claim—

The design for a mustache-guard clip herein shown and described.

WILLIAM DAN DALGLEISH.
